Patented Oct. 12, 1926.

UNITED STATES PATENT OFFICE.

MAX KAHN, OF BROOKLYN, NEW YORK.

COMBINED CORSET AND BRASSIERE.

Application filed May 20, 1922. Serial No. 562,300.

This invention relates to a combined garment, consisting in a single garment of a corset and brassière.

The object of the invention is to provide a combined garment of this character which is simple in structure, efficient for the purposes intended, and economical of manufacture.

Other objects of the invention will appear more fully hereinafter.

The invention consists substantially in the construction, combination, location, and relative arrangement of parts, all as will be more fully hereinafter set forth, as shown by the accompanying drawings, and finally pointed out in the appended claims.

Referring to the drawings:

Figure 1 is a rear view of the garment embodying my invention showing its application in practice.

Fig. 2 is a front view of the same.

Fig. 3 is a lay-out of the garment.

The same part is designated by the same reference numeral wherever it occurs throughout the several views.

In accordance with my invention I form the combined corset and brassière of front, back and side portions, the back portion, referring particularly to Fig. 3, is shown at 1, one side portion at 2, the other at 3, the corset front portions at 4 and 5 respectively, and the front flap portion at 6. The back 1 is provided a substantial distance up the face thereof with elastic material 7, reinforced, if desired, with two or more ribs 8, of such material as whale bone. The top of that portion of the back is pleated as at 9 to afford maximum expansion of the elastic portion 7. The respective fabric portions of the back 1 are cut to form, and are provided with tongues 10 and 11, to which are attached the usual elastics 12 for supporting garters. The tongues 10 and 11 are so positioned on the back portion 1 that the same come substantially at the side of the hips to afford free movement without binding. The side portion 2 extends the entire height of the combined garment, and is provided at its bottom with a portion 13, likewise formed of elastic material, to permit free movement, and at the same time a closely fitting garment. The side portion 3 of the garment is of half length with reference to the portion 2. The respective side portions 2 and 3 are sewed to, or formed integral with, the back portion 1. The edge of the back portion 1 which extends above the side portion 3 is provided with fastening devices of any suitable type, for example, eyes 14. The lower front 60 portions 4 and 5 are respectively connected to the side portions 2 and 3, or formed integral therewith, and each provided with a tongue 15 to form attachment to elastic or other type of garter supports 12. Similar 65 supports 12 are attached to the portion 1 at the tongues 10 and 11. The edge of the portion 4 is provided with the usual corset reinforcing strip 17, to which is secured the usual hooks 18, adapted to engage the pins 19, on reinforcing strip 20, formed on the edge of the front portion 5. The part of the garment thus far described constitutes the usual corset structure. The front flap portion of the garment consists 70 of the portion 6, which is sewed to the side portion 2, and is provided with any suitable attachment devices at its edge, for example, the hooks 21, adapted to engage in the eyes 75 14 of the back portion 1. Suitable shoulder straps 23 and 24 are provided, as is customary with brassières. From the foregoing description it will be readily seen that I have provided an exceedingly simple, closely fitting combination corset and brassière, especially adaptable for women's wear in 80 warm weather, where elimination of as many unnecessary garments as possible is desired. At the front of the front flap portion 6 of the garment may be provided an elastic, or other type of tape 26, provided with a hook 27, at the end thereof, for attachment with one of the pins 19 of the corset structure, to thereby tend to hold the front flap portion of the garment in a firm 85 position, and tend to prevent an objectionable rising of the front flap portion, which otherwise might result during the movements of the wearer. A garment of this structure, while inherently possessing the 90 advantageous attribute of adhering closely to the form or figure of the one wearing it, also serves the useful purpose of supporting the body of the wearer without hindrance 95 or binding, and at the same time performing all of the functions usual to corset and brassière structures.

Many modifications and changes in details will readily occur to those skilled in the art without departing from the spirit 110 and scope of my invention as defined in the claims, but having now set forth the ob-

jects and nature of my invention, and having shown and described a structure embodying the principles thereof, what I claim as new and useful and of my own invention, and desire to secure by Letters Patent is,—

1. A combination brassière and corset garment comprising a corset having front, side and back portions, a substantial part 10 of the central back portion being formed of an elastic material and a pleated part bordered by symmetrical body parts, and the lower part of the side portions being likewise formed of elastic material, and a 15 front flap secured to the upper part of one side portion and provided with means for detachable engagement with an upper side of the back portion, and shoulder straps secured to the back portion and the front 20 flap.
2. A combination brassière and corset garment comprising a corset having front, side and back portions, a substantial part of the central back portion being formed 25 of an elastic material and a pleated part bordered by symmetrical body parts, and

the lower part of the side portions being likewise formed of elastic material, and a front flap secured to the upper part of one side portion and provided with means for 30 detachable engagement with an upper side of the back portion, and an adjustable attachment between an edge of the front flap and the front portion of the corset.

3. A combination brassière and corset 35 garment comprising a corset having front, side and back portions, a substantial part of the central back portion being formed of an elastic material and a pleated insert, and the lower part of the side portions being 40 likewise formed of elastic material, and a front flap secured to the upper part of one side portion and provided with means for detachable engagement with an upper side of the back portion, and garter attachments 45 secured to the front and rear portions of the corset.

In testimony whereof I have hereunto set my hand on this 16th day of May A. D., 1922.

MAX KAHN.
